UNITED STATES PATENT OFFICE.

THOMAS DUDLEY SADLER, OF NEW ORLEANS, LOUISIANA.

HANDSAW GUIDE.

Application filed January 16, 1924. Serial No. 686,657.

To all whom it may concern:

Be it known that I, THOMAS DUDLEY SADLER, a citizen of the United States, residing at New Orleans, in the parish of Orleans and State of Louisiana, have invented certain new and useful Improvements in Hand-saw Guides; and I do hereby declare the following to be a full, clear, and exact description of the invention, such as will enable others skilled in the art to which it appertains to make and use the same.

The present invention relates to mitre boxes and saw guides, and more particularly to certain improvements therein.

An object of the present invention is to provide a saw guide, which may be applied directly to a board or the like to be cut, and which may then engage a saw and hold it to the work at the exact angle which was directly determined by application to the work, and to thus make it unnecessary to resort to measurements and the use of squares, and other devices for first ascertaining the desired angle and subsequently adjusting the mitre box or guide to such angle found.

Another object of the invention is to provide a measuring device and guide of this character which may be applied directly to the work, and which may be clamped thereon, so as to hold the saw guide in correct position after the same has been determined.

A further object of the invention is to provide a clamping means as a part of the measuring device, and which carries a locking lever constructed to cooperate with the parts of the measuring device for drawing in the clamp, and for locking the same after it has been engaged tightly with the work, the lever being adjustable to accommodate the measuring device to boards and the like of different widths.

The invention still further aims at the provision of an improved guide member, which is adapted to engage the saw and maintain the blade in correct alinement with the work and the measuring instrument, and which is detachably mounted on the instrument, so that the instrument may first be adjusted directly upon the work, and the saw guide may then be mounted on the instrument.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a top plan view of a hand saw guide constructed according to the present invention and as applied to the work.

Figure 2 is a similar view with the saw engaging member removed, the measuring instrument portion being clamped to the work and shown in full lines in position to cross cut the work and shown in dotted lines in position to cut the work diagonally.

Figure 3 is an enlarged outer edge elevation of the measuring instrument having the clamping bar removed therefrom.

Figure 4 is an enlarged transverse sectional view taken through the measuring instrument portion of the work on the line 4-4 of Figure 2 and showing the clamping member locked to the work.

Figure 5 is an enlarged end elevation of the saw engaging member or yoke removed from the instrument portion of the device.

Figure 6 is a longitudinal vertical section taken centrally through the saw engaging member substantially on the line 6-6 of Figure 5, and

Figure 7 is an enlarged fragmentary section taken through the saw engaging member substantially on the line 7-7 of Figure 5.

Figure 8 is a top plan view of a modification.

Figure 9 is an end view of the saw guide.

Figure 10 is a section on line 10-10 through same.

Figure 11 is a section on line 11-11 of Figure 8, and

Figure 12 is a section on line 12-12 of Figure 8.

Referring to the drawings 10 designates a board, plank or other piece of work which is to be cut upon some particular angle dependent on the character of the building or the like in progress of making.

The device of the present invention comprises a handle 11, which is of suitable length and thickness to be grasped and operated and which is provided with an inner flat edge adapted to lie against the edge of the work as shown in Figures 1 and 2, and which may comprise a pair of strap iron sections disposed at one end in closely spaced apart relation by a spacer block 12, and which has its opposite end portions offset away from each other and widely spaced

apart to accommodate a pair of filler blocks 13. The closely spaced apart ends of the straps constitute the inner end of the handle, and the straps carry a screw 14 provided with a winged nut 15 adapted to clamp the strap ends together, and upon a measuring blade 16 which is pivotally mounted on the screw 14 and adapted to be swung thereupon into different angles, such as illustrated in Figure 2. A friction washer 17 of leather or the like is preferably interposed between the upper face of the blade 16 and the upper strap of the handle, so as to frictionally bind the blade 16 in adjusted position. A retaining washer 18 is mounted upon the lower end of the screw 14 and between the head of the same, and the lower strap of the handle.

The handle 11 is adapted to be held and clamped against the edge of the work by a clamping bar 19 which, as best shown in Figures 2 and 4, comprises a flat strip of metal having a down-turned outer end 20 forming a clamping jaw adapted to engage over the edge of the work 10 remote from the handle 11. The clamping bar is adapted to extend through a guide slot 21 formed in the handle 11 intermediate the ends of the enlarged part thereof, and the slot 21 is formed in a bushing 22 seated in the upper block 13. The block 13 is provided with a wear plate 23 at its outer side and above the slot 21. The lower edge of the wear plate 23 is offset inwardly to provide a recess 24 in the plate in which is adapted to work the nose of a clamping and locking lever 25. The locking lever 25 comprises a flat metal bar of suitable length and width for easy handling, and which has rounded opposite ends forming noses arranged to engage in the depression 24 one at a time, and the lever 25 has extending from opposite sides headed studs 26, which are spaced unequally from the adjacent ends of the lever 25 to provide working noses of different lengths. The studs extend from opposite sides of the lever 25, so that when one stud is extending downwardly, the other stud is extending upwardly to form a handle. The clamping bar 19 is provided with a series of openings 27 of a size adapted to snugly receive the heads of the studs 26 therethrough, and the studs 26 having their shanks of sufficient length to permit the overlapping of the heads of the studs against the lower side of the clamping bar 19, after the lever 25 has been fitted in the selected opening 27.

The studs 26 are so arranged with respect to the adjacent ends of the clamping lever 25 as to form therewith cams, so that after the lever 25 is fitted into an adjacent opening 27 at the outer side of the handle 13, the lever 25 may be swung outwardly into the position shown in Figures 1, 2 and 4, so as to first draw the clamping bar 19 through the handle 11 and bind the claw 20 of the

clamping bar against the work, and to then lock the clamping bar in such position by moving the lever 25 into a dead center position. After this is done the blade 16 may be swung into the desired angle at which it is necessary to clamp the work. After this is done the saw engaging member is then mounted on the blade 16.

The saw engaging member may be of any suitable construction adaptable for mounting upon the blade 16, but in the present case is shown as comprising a yoke or body portion 28 composed of a pair of angle members having base portions 29 adapted to rest directly upon the face of the work 10, and so having their major portions extending upwardly in closely spaced apart relation, and secured in such relative positions by a bridge piece 30, which connects the upper ends of the angle members. This yoke is adapted to receive therein a blade 31 of a saw as shown in Figures 1 and 7. The angle members are provided at opposite edges with inwardly and oppositely facing vertical guide ways 32, which may be formed with removable strips 33 at their outer sides, so that access may be readily had to the guide ways 32.

Slides 34 are mounted in the guide ways 32, and are in the form of spaced apart blocks 35 connected together at their upper ends, and having mounted therein a roller 36 arranged in the bight of the slide and adapted to engage the upper edge of the saw blade 31. The lower ends of the blocks 35 have inwardly extending contact jaws 37 which are closely spaced apart and adapted to engage against the opposite sides of the saw blade 31, to hold the same from vibrating, and to also hold it in true alignment in the guide or yoke member 28.

The back edge of the blade 31 is usually reinforced by an over-turned stiff strip forming a thickened back edge for the saw and this enlarged edge is accommodated between the contact jaws 37 and the roller 36, the latter bearing directly on the edge and supporting the slide 34 on the saw. There is a slide 34 provided at each end of the guide member 28, so that the slides engage the saw blade 31 at longitudinally spaced points to thus maintain the saw blade in true alignment, and prevent the lateral deflection thereof by the hand during the act of reciprocating the saw.

The slides 34 are adapted to rise and fall with the saw blade not only in its rocking and reciprocating movement, but also in the positioning of the saw at different angles on the work. The advantages of such a structure is that the bottom of the saw guide is open, so that the saw blade may be inclined at the desired convenient angle and it does not necessarily have to be held in a true horizontal position, such as is the case when using the ordinary type of mitre box.

One of the base flanges 29 of the yoke member 28 has a horizontal slot 38 therein which is located near the lower edge of the base member 29 and of a suitable width and thickness to receive the adjustable blade 16. The saw guide is adapted to be slipped upon the blade 16, as shown in Figure 1 after the blade 16 is adjusted to the required angle. The clamping bar 19 holds the measuring instrument, and also the saw guide in proper position upon the work. It is readily seen that applicant's device may be applied to work which is of such a construction that it can not be placed in a mitre box, and it is also apparent that the device may be correctly positioned upon the work without the exercise of skill and care in measuring the correct angles upon the work, and subsequently adjusting the mitre box and work in the mitre box to the required angles. The angle is obtained by adjusting the blade 16, and then the saw guide is slipped upon the blade and moved to the desired position, and may be adjusted along the blade during use, so as to accommodate the guide to work which may be relatively wide.

The slides 34 may be introduced and removed through the bottoms of the guide ways 32, and may be held in place by a removable pin or screw 39 adapted to engage the slides when the latter move into their lowermost positions.

The measuring instrument or try-square may of course be of any suitable construction and in the present instance the blade 16 is shown as provided with a row of graduations 40 along one edge, and a series of apertures 41 spaced at predetermined intervals along the scales of graduations, and adapted to receive therethrough the point of a pencil, so as to mark off the work in parallel lines when desired, and by the longitudinal sliding movement of the handle along the edge of the work.

It is apparent that when the clamping bar 19 is secured in position by the lever 25 upon a piece of work, as shown in Figure 2, the blade 16 may be loosened by the winged nut 15, and the blade 16 swung into the desired angle, such as shown in dotted lines in Figure 2 and in full lines in Figure 1. This adjustment of the blade 16 is to show the required angle at which the work is to be cut, and the angle may of course be determined by applying the instrument to the end of a piece of work, which has already been cut or finished, so as to determine the necessary cut of the new piece of work for interfitting with the first piece. As soon as the try-square is adjusted and clamped in position, the saw guide may then be engaged over the blade 16, by projecting the blade 16 in the slot 38, and the saw guide may be slid along the blade 16 to the desired position for controlling the saw, and for admitting access to

the work at an angle which best suits the carpenter.

The clamping lever 25 may of course be quickly released from the clamping bar 19 by swinging the lever 25 to one side, such as to the right according to the construction shown in the drawings, so as to ease up or release the clamping bar 19. The nose of the clamping bar 19 works in the recess or slot 24, and the upper wall of the slot 24 holds the clamping lever 25 from lifting out of the opening 27 of the clamping bar, so that the headed stud 26 which projects downwardly through the clamping bar 19 cannot be accidentally lifted or sprung out of interlocking engagement with the clamping bar. The recess 24, however, is of a slight depth, so that when the lever 25 is turned into substantially right angular relation relatively to the clamping bar 19, the inner edge of the lever 25 is spaced sufficiently far from the handle 11 to free the lever 25, and permit of the withdrawal of the adjacent stud 26 from the clamping lever 19. In this manner the locking lever 25 may be quickly and easily removed, and positioned relatively to the openings 27 for accommodating work of different widths. It will be noted that the openings 27 are arranged in staggered relation, so as to dispose the same in substantially overlapped relation to obtain relatively fine adjustments of the lever 25 on the clamping bar. This arrangement of the openings 27 together with the disposition of the studs 26 at different distances from the opposite ends of the lever 25 provides for a minute adjustment of the clamping lever to thus accommodate the device to work of practically any width within practical limits.

In the modified forms shown in Figures 8 to 12, inclusive, the try-square comprises a handle or runner 50 which may comprise a block of wood of suitable length and provided with straight opposite edges adapted to lie against the edge of the work, and which may have a face plate 51. The face plate 51 may extend beyond one end of the block 50, as shown in dotted lines in Figure 8, and carries a threaded bolt 52 upon which is pivoted a blade 53 adapted to be swung across the work at the desired angle, and which may be clamped in position by a winged nut 54 mounted on the bolt 52.

The handle 50 also carries a second threaded bolt 55 arranged intermediate the ends of the block 50 and projecting upwardly from the face plate 51. The bolt 55 passes through a slot 56 formed longitudinally in a clamping blade 57 adapted to extend across the work and provided upon its remote end with a depending flange or jaw 58 adapted to engage against the remote edge of the work. The slot 56 permits of the longitudinal adjustment of the blade 57 over the handle 50,

and a winged nut 59 mounted on the bolt 55 may be used for clamping the blade 57 firmly to the handle when adjusted.

It will be noted that there are no projections above the upper face plate 51 of the block or handle so that the blades 53 and 57 may be swung lengthwise of the handle and the try-square may then be packed in a small space or in a shallow tool chest or the like.

10 The adjusting blade 53 carries a removable saw guide which comprises a base plate 60 adapted to rest on the work, and which carries a second plate 61 of reduced width and which is spaced from the plate 60 by strips 15 62 providing a channel 63 between the plates 60 and 61. The channel 63 is of suitable dimensions for slidably receiving the blade 53 therethrough. The plate 61 carries a bearing block 64 therein with an axis of the bearing extending transversely of the plate 61 and in which is disposed the shaft portion 20 65 of an upright 66 mounted on the outer end of the shaft portion and which carries a pair of spaced apart bars 67 secured together at their upper ends only by rivets 68 25 or the like and between which is clamped a spacing block 69. A guide way or groove 70 is thus formed between the bars 67 for the reception of a saw blade. The groove 70 is 30 of sufficient width to snugly receive the saw blade, so as to hold it from vibrating without interfering with its free reciprocating movement. The bars 67 have inner opposite flat faces to guide the blade and determine 35 its true position across the work according to the angle at which the blade 53 and the saw guide is adjusted.

The upright 66 is mounted on the shaft 40 65 so that the upright with its bars 67 may be swung toward the plane of the base plate 60, so that the device may be compact and placed in a small compartment when not in use. In order to hold the upright 66 when raised, adjustable brace rods 71 are 45 provided, one at each side of the upright 66 having their upper ends attached to an eye 72 mounted on the upper end of the upright 66 and having their lower ends secured to eyes 73 which are carried by the frame or 50 lower portion of the saw guide at opposite sides of the bearing 64.

With this type of the device the parts may be readily folded into compact form, so as to occupy but small space, and the parts 55 may be quickly and easily set up and applied to the work in different positions of adjustment.

The clamping blade 57 may be provided with pencil receiving openings 74 arranged 60 in suitable position and relation for drawing parallel lines on the face of the work when desired.

It is obvious that various changes and

modifications may be made in the details of construction and design of the above specifically described embodiment of this invention without departing from the spirit thereof, such changes and modifications being restricted only by the scope of the following claims:—

What is claimed is:—

1. An instrument as specified comprising a handle having a straight edge adapted to be placed against one edge of a piece of work, a pair of blades adjustably mounted on the handle, clamping means carried by one blade to engage the work for holding the handle and the blades in adjusted position thereon, said other blade having straight parallel edges and being adapted for adjustment on the handle across the work into various angles for use as a straight and a bevel edge, a saw guide removably and adjustably mounted on said other blade for supporting and guiding a saw across the work at the desired angle, said saw guide being adapted to be slid from said blade for freeing the straight edge thereof.

2. A saw guide comprising a handle having a straight edge adapted to be placed against one edge of a piece of work, a pair of blades adjustably mounted on the handle for engagement across the upper surface of the work, one of said blades having clamping means thereon for engaging the work to bind the handle and the blades thereto, said other blade having straight parallel edges, said blades being adapted for adjustment relatively to the handle for folding the handle and the blades into compact form, and a collapsible guide removably and adjustably mounted on the other of said blades for guiding a saw at the desired angle across the surface of the work, said guide being removable from said blades for exposing an uninterrupted straight edge of the blade in position across the work.

3. A saw guide comprising a handle having a flat upper face, a pair of blades pivotally mounted upon the upper face of the handle and adapted to extend across the work, one of said blades having a depending jaw member adapted to engage the remote edge of the work, said blades being adapted to be swung lengthwise of the handle for holding the device, clamping means for securing the blades in adjusted position, a saw engaging member detachably mounted on the other blade, a foldable guide carried upon said member, and adjustable means for holding said foldable guide in upright position to engage a saw blade and adapted to be released for folding the guide.

THOMAS DUDLEY SADLER.
